Primary Examiner — Omeed Agilee*Assistant Examiner* — Eric Eldone Tormanen(57) **CLAIM**

The ornamental design for a foot drop brace, as shown and described.

DESCRIPTION

FIG. 1 is a perspective view of a foot drop brace in a secured state, showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view of the foot drop brace in an unsecured state.

The broken lines in the drawings depict portions of the foot drop brace that form no part of the claimed design.
